CLAIM

The ornamental designs for a pet treat, as shown and described.

DESCRIPTION

FIG. 1 is a perspective view of a new design for a pet treat, illustrating a front, side, and bottom view;

FIG. 2 is a front elevation view of the pet treat shown in FIG. 1;

FIG. 3 is a rear elevation view of the pet treat shown in FIG. 1;

FIG. 4 is a top plan view of the pet treat shown in FIG. 1;

FIG. 5 is a bottom plan view of the pet treat shown in FIG. 1;

FIG. 6 is a side elevation view of the pet treat shown in FIG. 1;

FIG. 7 is another side elevation view of the pet treat opposite the side elevation view shown in FIG. 6;

FIG. 8 is a perspective view of a second design for a pet treat, illustrating a front, side, and bottom view;

FIG. 9 is a front elevation view of the pet treat shown in FIG. 8;

FIG. 10 is a rear elevation view of the pet treat shown in FIG. 8;

FIG. 11 is a top plan view of the pet treat shown in FIG. 8;

FIG. 12 is a bottom plan view of the pet treat shown in FIG. 8;

FIG. 13 is a side elevation view of the pet treat shown in FIG. 8;

FIG. 14 is another side elevation view of the pet treat opposite the side elevation view shown in FIG. 13;

FIG. 15 is a perspective view of a third design of a pet treat, illustrating a front, side, and bottom view;

FIG. 16 is a front elevation view of the pet treat shown in FIG. 15;

FIG. 17 is a rear elevation view of the pet treat shown in FIG. 15;

FIG. 18 is a top plan view of the pet treat shown in FIG. 15;

FIG. 19 is a bottom plan view of the pet treat shown in FIG. 15;

FIG. 20 is a side elevation view of the pet treat shown in FIG. 15;

FIG. 21 is another side elevation view of the pet treat opposite the side elevation view shown in FIG. 20;

FIG. 22 is a perspective view of a fourth design of a pet treat, illustrating a front, side, and bottom view;

FIG. 23 is a front elevation view of the pet treat shown in FIG. 22;

FIG. 24 is rear elevation view of the pet treat shown in FIG. 22;

FIG. 25 is a top plan view of the pet treat shown in FIG. 22;

FIG. 26 is a bottom plan view of the pet treat shown in FIG. 22;

FIG. 27 is a side elevation view of the pet treat shown in FIG. 22;

FIG. 28 is another side elevation view of the pet treat opposite the side elevation view shown in FIG. 27;

FIG. 29 is a perspective view of yet a fifth design of a pet treat, illustrating a front, side, and bottom view;

FIG. 30 is a front elevation view of the pet treat shown in FIG. 29;

FIG. 31 is rear elevation view of the pet treat shown in FIG. 29;

FIG. 32 is a top plan view of the pet treat shown in FIG. 29;

FIG. 33 is a bottom plan view of the pet treat shown in FIG. 29;

FIG. 34 is a side elevation view of the pet treat shown in FIG. 29; and,

FIG. 35 is another side elevation view of the pet treat opposite the side elevation view shown in FIG. 34.

The shading lines shown in the drawings represent three-dimensional surface contour only and do not depict any texture, color, shading, or other characteristic.
